United States Patent Office

Des. 188,413
Patented July 19, 1960

188,413

BOOM TURNTABLE

Daniel F. Przybylski, Winona, Minn., assignor to The Warner & Swasey Company, Cleveland, Ohio, a corporation of Ohio

Filed July 16, 1959, Ser. No. 56,805

Term of patent 14 years

(Cl. D14—3)

Fig. 2

Fig. 1 is a top perspective view taken from the rear and left side of the boom turntable embodying my new design; and

Fig. 2 is a top perspective view thereof taken from the front and right sides.

The phantom showing of the boom is for illustrative purposes only.

What I claim is:

The ornamental design for a boom turntable, substantially as shown and described.
